UNITED STATES PATENT OFFICE.

LAWRENCE RICHARDSON, OF CHICAGO, ILLINOIS.

TRUCK-SPRING ARRANGEMENT.

Application filed August 28, 1924. Serial No. 734,591.

This invention relates to a truck spring arrangement.

In the Pullman truck construction, the rocking of the car is minimized by a special arrangement in which the load is transmitted from the center plate through the H spider bolster, elliptical springs, side frames, helical springs, equalizers to the journal boxes. While such arrangement is satisfactory in passenger car trucks, it is too heavy and expensive for freight car trucks. At the same time, excessive rocking of freight cars is to be prevented, among other things, to avoid derailments.

Accordingly, one object of this invention is to provide a simple, reliable and efficient truck spring arrangement for minimizing rocking of the car.

Another object is to provide a differential spring arrangement adapted to minimize the rocking of a railway car in a manner to meet all of the requirements under service conditions.

These and other objects are accomplished by means of the arrangement disclosed by the single figure of the drawings which is a fragmentary side elevation of a railway car truck embodying my invention.

In this particular instance, the invention is disclosed in connection with a four-wheel truck, including a side frame 10 having a compression member 11, a tension member 12, bolster columns 13 forming an opening 14 for the reception of a bolster 15 which is supported upon a spring combination embodying my invention.

In this arrangement, the bolster 15 rests directly upon a plurality of coil springs 16 which have a given capacity and periodicity for absorbing shocks and returning the car to a state of equilibrium. It is found that coil springs as ordinarily used, however, permit rocking which at times becomes excessive to the extent that a car may be derailed.

To overcome such excessive rocking, I have provided a spring arrangement in which the coil springs 16 cooperate with a plurality of elliptical springs 17 having a periodicity which differs from that of the coil springs, so that one set of springs will have a differential action, one upon the other. As shown, the elliptical springs 17 are in the form of curved plates which are in frictional engagement with each other and are located within a suitable housing

18, which rests upon or forms a part of a spring plank 19 connecting the side frames. A horizontal plate 20 separates the elliptical springs from the coil springs and forms a seat for the latter and is pocketed or guided in its vertical movements by the pocket member 18.

From the arrangement shown, it will be appreciated that if the coil springs have a given periodicity so that they flex more readily than the elliptical springs, that under the rocking influence of a car body the coil springs 16 will be compressed to a maximum before the elliptical springs of less periodicity fairly start to flex to absorb the shock, and the coil springs will begin to expand before the elliptical springs have taken on their maximum flexure for that particular shock. Under the circumstances, it will be seen that the coil springs and the elliptical springs will have a differential action, one upon the other, resulting in breaking up the rocking action of the car and minimizing such action. In addition preferably elliptical springs of the type shown wherein there is frictional engagement of the spring plate members 17 are employed whereby an increased snubbing action is effected because of the frictional engagement of the elliptical spring plate members 17.

While I have shown the invention as applied to a four-wheel truck, it will be understood that the invention may be used in connection with car trucks having a different number of wheels.

I claim:

1. In a railway car truck, the combination of a load transmitting member, and differential means for supporting said load transmitting member and acting in the same direction for minimizing rocking of the car and including groups of springs of different character, one of said groups of springs comprising frictional engaging members.

2. In a railway car truck, the combination of a side frame having a bolster opening, a bolster mounted in said opening, coil springs in said bolster opening upon which said bolster is mounted, and elliptical springs upon which said coil springs are mounted, said coil and elliptical springs having different periodicities for causing a differential action one upon the other for minimizing rocking of the car.

3. In a railway car truck, the combina-

tion of a side frame having a bolster opening, a bolster mounted in said opening, coil springs upon which said bolster is mounted, and elliptical spring members having frictional engagement with each other for increasing the snubbing action and upon which said coil springs are mounted, said

coil and elliptical springs having different periodicities for causing a differential action one upon the other for minimizing rocking 10 of the car.

Signed at Chicago, Illinois, this 22nd day of August, 1924.

LAWRENCE RICHARDSON.
